UNITED STATES PATENT OFFICE.

THOMAS J. NAULTY, OF PHILADELPHIA, PENNSYLVANIA, ASSIGNOR TO THE J. G. BRILL COMPANY, OF PHILADELPHIA, PENNSYLVANIA, A CORPORATION OF PENNSYLVANIA.

DOOR-OPERATING MECHANISM FOR PASSENGER-CARS.

1,068,265.

Specification of Letters Patent.

Patented July 22, 1913.

Application filed March 8, 1911. Serial No. 613,136.

To all whom it may concern:

Be it known that I, THOMAS J. NAULTY, a citizen of the United States, residing in Philadelphia, Pennsylvania, have invented 5 certain Improvements in Door-Operating Mechanism for Passenger-Cars, of which the following is a specification.

One object of this invention is to construct a simple and effective means for operating 10 the hinged doors which close one side of the platform of a passenger car.

Another object of the invention is to locate the door operating mechanism overhead so that it will be completely out of the 15 way and to provide means, within easy reach of the conductor or motorman, for operating the mechanism to open and close the doors.

The invention further relates to certain 20 details of construction which will be fully described hereafter.

In the accompanying drawing:—Figure 1, is a sectional plan view of a portion of the rear platform of a car illustrating my invention; Fig. 2, is a transverse sectional view on the line 2—2, Fig. 1, showing the doors closed; Fig. 3, is a view similar to Fig. 2, showing the doors in the open position; and Fig. 4, is a sectional plan view of one 30 part of Fig. 1, showing the doors in the open position.

A is the body of the car.

B is the platform.

B' is the vestibule casing of the platform.

35 D and E are the pivoted doors for closing one side of the platform. These doors, in the present instance, are made in two sections, D', D² and E', E², respectively.

d and e are the vertical pivot shafts on 40 which the inner sections D' and E' of the doors are mounted; the outer sections D² and E² being pivotally mounted on the inner sections by hinges d' and e', respectively.

On the outside of the section D², near its 45 upper edge, is a bracket carrying a vertical guide roller d², and on the section E² is a bracket carrying a vertical roller e². These two rollers are adapted to travel between rails a in the heading a' of the door frame, 50 which is located, in the present instance, directly under the roof b of the platform.

On the end of the pivot shaft d is an arm f which is connected by a rod f' to an arm i on a rock shaft I. This rock shaft is arranged longitudinally in respect to the car 55 and comparatively close to the side of the platform and mounted, in the present instance, in bearings h, h secured to the roof b of the platform. On the vertical pivot shaft e is an arm g connected by a rod g' 60 to an arm i' on the rock shaft I. On the shaft I, in the present instance, and located about mid-position between the two arms i, i', is the operating lever N. This lever is secured to the shaft I and one arm 65 n of the lever has a depending rope or strap m provided with a handhold, and the other arm n' has a depending rope or strap m' also provided with a handhold. The arms in the present instance are arranged at right 70 angles to the arms i, i' on the shaft I.

When the lever N is in the position illustrated in Figs. 1 and 2, the doors are in the closed position, but by pulling down upon the cord or strap m the sections D' and E' 75 of the doors are turned on their pivots to the open position as in Fig. 2, and the sections D² and E² are turned on their hinges and are guided so as to assume the position illustrated in Figs. 3 and 4. In the present 80 instance the platform is divided by a rail C or other barrier, forming ingress and egress passageways; b' being the ingress passageway and b² being the egress passageway, and the conductor stands back of the rail C in 85 the egress passageway; the depending cords or straps being so located as not to interfere with the movement of passengers to and from the car. The position of the lever N may be varied, depending upon the type of 90 car to which the invention is applied, and the longitudinal shaft I may be located at any distance desired from the doors, also depending upon the type of car.

I claim:—

The combination of two doors arranged side by side; a vertical pivot shaft for each door; an arm on the upper end of each pivot shaft; a longitudinal overhead rock shaft located back of the doors; two arms on the 100 rock shaft; a rod connecting one arm of the shaft with the arm of the pivot shaft of one

door; a rod connecting the other arm of the rock shaft with the arm on the pivot shaft of the other door; with a two-armed lever secured to the shaft and having depending operating means by which the said shaft is rocked to move the doors to the open or closed position.

In testimony whereof, I have signed my name to this specification, in the presence of two subscribing witnesses.

THOMAS J. NAULTY.
